UNITED STATES PATENT OFFICE.

CHARLOTTE C. PETERSON, OF OGDEN, IOWA.

ENVELOP.

SPECIFICATION forming part of Letters Patent No. 739,505, dated September 22, 1903.

Application filed April 30, 1903. Serial No. 155,051. (No model.)

To all whom it may concern:

Be it known that I, CHARLOTTE C. PETERSON, a citizen of the United States, residing at Ogden, in the county of Boone and State 5 of Iowa, have invented certain new and useful Improvements in Envelops; and I do hereby declare the following to be a full, clear, and exact description of the invention, such as will enable others skilled in the art to 10 which it appertains to make and use the same.

My invention has relation to envelops; and it consists of certain novel features of construction, combination, or arrangement of parts, as will be hereinafter clearly set forth.

15 The prime object of my invention is to provide an envelop which may be reliably sealed and will be practically impossible to unseal the same without disclosing that the envelop has been tampered with.

20 Other objects and advantages will be hereinafter made clearly apparent, reference being had to the accompanying drawings, which are made a part of this application, and in which—

25 Figure 1 shows a blank from which my improved envelop is formed. Fig. 2 is a perspective detail view of the blank shown in Fig. 2 in the process of being folded, so that the various parts thereof will each be disposed 30 in its respective operative position. Fig. 3 shows a transverse section of Fig. 2, taken on or near the median line thereof. Fig. 4 is a similar view to that presented in Fig. 3, showing one of the flaps folded parallel with a contiguous part of the body of the envelop. Fig. 35 5 is a similar view to that presented in Fig. 4, indicating a further progress in the folding of the securing-flap, while Fig. 6 shows a transverse central section of the completed 40 envelop. Fig. 7 shows a slightly modified form of construction for the flap of the envelop.

In order to conveniently refer to the various details of my invention and coöperating 45 accessories deemed necessary in carrying out my invention, numerals will be employed, the same numeral referring to a similar part throughout the several views.

50 Referring to the numerals on the drawings, 1 indicates the front or main body portion of the envelop, which is provided with the end sections 2 and 3, preferably of triangular form,

though the points thereof may be variously shaped, as will be understood. The body portion 1 is also provided with the edge extension 4, which comprises the flap of the finished envelop, which is left open, as is common, until it is desired to seal or close the same for mailing.

Upon the opposite side of the body-section 60 from that occupied by the flap 4 I provide the member 5, having the anchoring-terminal divided into the folding-flap sections 6 and 7, said sections being designated by dotted lines, said lines indicating where said anchoring- 65 flaps are to be folded, as more fully shown in Figs. 3, 4, 5, and 6.

The flap-section 6, it will be understood, is to be gummed upon both sides, while the section 7 is to be gummed only upon its inner 70 surface, and it is therefore obvious that by dampening said gummed surfaces the sections may be folded down upon each other and upon a contiguous part of the section 5, thereby disposing said parts in their respective operative positions, it being understood that the free edge of the flap 4 shall first be interposed between the sections 6 and 7.

In Fig. 5 the flap 4 is folded downward, 80 whereby its free edge will be disposed immediately above and in contact with the gummed surface of the section 6, when by folding down the section 7 the flap is securely engaged between said members. It will of course be understood that the entire free edges of the flap-sections 4 and 5 may be gummed upon their inner sides, whereby when said parts are folded down upon a contiguous part or edges of the sections 2 and 3 the latter will be reliably engaged and held in place, thereby completely sealing the envelop. By interposing 85 the free edge of the flap 4 between the gummed surfaces of the sections 6 and 7 it will be next to impossible to unseal the envelop after it has been closed, especially since both surfaces 90 of the section 6 are gummed. In some instances I prefer to form the slight extension or tongue 8 upon the flap 4, said flap being made of slightly shorter length, whereby said tongue 8 may be inserted through a suitable 95 slit provided in a contiguous part of the section 6, thus enabling said tongue to protrude entirely through said slit, and thereby rest between the inner side of said section and a 100

contiguous part of the gummed surface of the member 5.

In Fig. 7 I have shown the tongue 8 as being formed upon the free edge of the flap-section 4, it being obvious that a suitable slit 5 may be readily formed in the section 6 to receive the same, and I therefore deem it unnecessary to illustrate the exact location of said slit.

10 Having thus fully described my invention, further reference to the details thereof is deemed unnecessary.

What I claim as new, and desire to secure by Letters Patent, is—

15 The herein-described envelop, comprising the body portion 1, members 2 and 3, flap-sections 4 and 5 gummed on their inner edges, a

section 6 formed integral with said flap 5, said section being gummed on both sides and a section 7 formed integral with the section 6 ^{2c} and gummed upon its inner side, said sections having their ends cut substantially V-shaped whereby when said sections are folded and pasted together the ends thereof will conform to the converging edges of the flaps 4 ²⁵ and 5, substantially as and for the purpose set forth.

In testimony whereof I affix my signature in presence of two witnesses.

CHARLOTTE C. PETERSON.
